COMBINATION SWITCH AND VARIABLE
RESISTOR

Stanley O. Bender, Asheville, N.C., assignor to CTS Corporation, Elkhart, Ind., a corporation of Indiana
Filed Nov. 29, 1961, Ser. No. 155,555
7 Claims. (Cl. 338—172)

This invention relates generally to a combination variable resistor and switch, and, in particular, to a combination variable resistor and switch specifically designed to effect an economy in parts so that the control will occupy a minimum amount of space.

In the hearing aid field, where the entire unit is to be mounted in the temple of the eyeglasses of the wearer, it is extremely important that the controls for the hearing aid be as physically small as possible. It is also advantageous to combine the two controls that need to be operated by the wearer: the on-off switch and the volume control. By combining these controls, only one control knob is needed which greatly simplifies the construction of the housing for the unit. Also in the case of the temple mounted unit, it is important to have only one control knob, since the operator will usually want to make adjustments while wearing his glasses, and consequently, will not be able to watch what he is doing. With only one control knob to adjust, there will be no possibility of his turning the wrong knob.

Further, by combining the switch and volume control and arranging the switch to be operated at the point where the volume is the lowest, the possibility of turning on the unit with the volume control set high with the irritating blast of sound that follows, is eliminated.

Therefore, it is the principal object of this invention to provide an extremely small combination variable resistor and switch. It is an additional object of this invention to provide a combination variable resistor and switch which employs a minimum number of parts and which employs parts which are common to both the variable resistor and switch but which perform different functions for each.

It is also an object of this invention to provide a switch which is so arranged and constructed that the movable contact moves into and out of engagement with the stationary contact with a wiping action.

The invention consists of a combination variable resistor and switch. The variable resistor has a base, a knob rotor or contact carrier and a shaft with the usual terminals, contacts, and a resistive path supported by the base. The shaft is fixed to the base and rotatably supports the knob rotor, and also holds the rotor in position against the base. It also functions as the stationary contact of the switch while on the other side it acts as one terminal of the switch. By forming the rotor and the base with appropriate cavities which complement each other, the inner workings of the variable resistor can be housed by these members. The switch consists of a stationary contact and a movable contact, and means for moving the two contacts into and out of engagement. The stationary contact is provided by the end of the shaft which extends out from the rotor side of the control. The movable contact is a U-shaped member of resilient material which is arranged with one arm attached to the base and one arm in position against the end of the shaft on the opposite side from the base. The means for moving the movable contact to open and close the switch is located on the rotor and consists of a cam which engages the movable contact and forces it out of engagement with the shaft during a portion of the rotation of the rotor. In addition, a boss is provided on the end of the shaft acting as the stationary contact which makes point contact with

2

the movable contact in such a way that the operating means causes a lateral and longitudinal movement as well as a vertical movement between the contacts when the switch is opened and closed. This lateral and longitudinal movement results in a wiping action between the contacts when the switch is opened and closed which is very desirable.

Another important feature of the invention is the unique design which combines the variable resistor and switch in such a way as to realize a real economy of parts, thus allowing a substantial reduction in the overall size of the control.

The invention will now be described in detail in connection with the attached drawings in which:

FIGURE 1 is a side view of the control looking at the base side;

FIGURE 2 is a side view of the control showing the rotor side—the opposite side from FIGURE 1;

FIGURE 3 is a top view of the control showing the terminals of the variable resistor;

FIGURE 4 is a cross-section through the control taken along line 4—4 in FIGURE 3;

FIGURES 5 and 6 show the cam action which opens and closes the switch;

FIGURE 7 is an enlarged view of the switch contact illustrating the wiping action which occurs when the switch is opened and closed; and

FIGURE 8 is a top view of a portion of the stationary contact illustrating the path followed by the point of contact between the two contacts as the switch is opened and closed.

In describing the control in detail, we will first discuss the arrangement of the members as they perform the function of a variable resistor and then we will discuss the components which make up the switch section of the control.

The three large components of the variable resistor are the base 10, the rotor or knob 11 and the shaft 12. The shaft has an enlarged head 13 and three sections of varying diameter indicated at 14, 15, and 16.

The base 10 is provided with an opening through its center approximately the same size as the section 15 of the shaft so that by placing the base on this section of the shaft, against the shoulder formed between the two sections 14 and 15 and staking the shaft as shown at 17, the base is permanently assembled on the shaft.

The knob 11 is also equipped with a hole through its center. This hole is slightly larger than section 14 of the shaft so that when assembled in the manner shown in FIGURE 4, the rotor 11 will be free to rotate on the shaft, with respect to both the shaft and the base 10. The rotor is, of course, held on the shaft by the enlarged head 13 and the base 10.

The rotor is also equipped with an annular ring 18 which provides an annular cavity to house the current carrying members of the variable resistor. The flange or ring 18 also has a portion 19 of increased thickness which is arranged to engage the lug 20 on the base to limit the amount of rotation of the rotor in each direction.

The current carrying members of the variable resistor are the resistive element 21, which is mounted on the base and which is arcuate in the conventional manner; the contactor 22, which is attached to the rotor 11 and which moves along the resistive element 21 as the rotor rotates on the section 14 of the shaft 12; and the center connector 23, which contacts the contactor. Terminal 24, which is connected to the center connector, extends outside of the control to provide means for connecting the unit into an electrical circuit as also do terminals 25 and 26 which are connected to the ends of the arcuate resistive path 21. The portion 19 of the flange 18 and

the lug 20, described above, are usually arranged so that the contactor will not travel past the end of the arcuate path in each direction.

Both the base 10 and the rotor 11 are made of non-conductive insulating material to allow the variable resistor to be adjusted without any danger of shock to the operator. To assist in the adjusting of the variable resistor, teeth 27 are provided on the periphery of the rotor.

The switch which forms part of this unit comprises the stationary contact 29 which is a spherically shaped boss on the enlarged head 13 of the shaft 12, and the movable contact 30, which is shown as an integral part of the arm 31 of the U-shaped member 32. The U-shaped member is made of resilient conductive material such as brass. It is formed with two arms which are arranged to embrace the control so that the arms engage opposite sides thereof. The arm 31, which as described above acts as the carrier of the movable contact 30, is arranged to resiliently hold the contact against the stationary contact 29. The other arm 33 is attached to the base of the variable resistor by an adhesive resin or other appropriate means.

The other arm 33 is equipped with the outwardly extending members, 34 and 35, which provide a terminal for the switch and which also act as locating lugs for mounting the unit. As illustrated, these members are integral parts of the arm 33, and are formed from this arm simply by cutting and bending a portion of the metal outwardly at a 90° angle therefrom. The arm 33 is also provided with a key hole shaped opening 36, which is sufficiently large to allow the arm to be attached to the base 10 and yet be spaced from the end 16 of the shaft 12 which acts as the other terminal of the switch. The key hole shaped opening facilitates the assembly of the unit.

The opening and closing of the switch is accomplished by the cam 37, which is carried by the rotor 11. The cam has a curved surface 38 and a flat surface 39 as illustrated in FIGURES 5 and 6. To improve the switch action and to provide an inclined surface to engage the cam 37, a portion of the arm 31 is bent downward to form a V-shaped protrusion 40, which has the two inclined sides 41 and 42 as also shown in FIGURES 5 and 6. This protrusion is located in the path of the cam 37 so that the curved surface 38 of the cam will engage the inclined surface 42 and force the arm 31 upwardly, moving the movable contact 30 out of engagement with the stationary contact 29 thereby opening the switch. After the protrusion 40 has moved out of engagement with the curved surface of the cam, it engages the flat surface 39, which is a sufficient distance above the rotor to maintain the switch open. This surface may be of varying lengths, depending upon the number of degrees of rotation the switch open condition is desired. For example, in the commercial embodiment of this unit, the switch is open for approximately 20° of rotation of the rotor. The curved surface 38, is approximately twice the height of the flat surface 39, so that the operator will feel a snap action when the switch moves from a closed to open condition and vice-versa.

Another important feature of this invention is the wiping action which occurs between the contacts when the switch is opened and closed. This wiping action is the result of the shape and arrangement of the contacts plus the fact that the movable contact is carried by a resilient member which is capable of moving laterally and longitudinally, as well as vertically. When the switch is opened and closed, the arm 31 is moved vertically upward moving the contact 30 out of engagement with the stationary contact 29. This movement, greatly enlarged of course, is illustrated in FIGURE 7. By forming the contacts with generally spherical surfaces and by offsetting the central axes of the spherical surfaces, the point of contact between the two contacts will move from the point A to the point B (the distance C) when the switch is closed due to the force being exerted by the spring arm 31. In

other words, when the contact 30 is allowed to move downward to first engage the contact 29, it will do so at the point A. Then as the spring 31 continues to exert a downward force on the contact, the resultant horizontal component of this force will cause the arm 31 to move longitudinally allowing the contact 30 to move down the contact 29 to the point B. When the switch is opened the reverse occurs, of course, and the point of contact between the contact 30 and contact 29 moves from the point B to the point A before they break engagement.

This wiping motion as described above and as illustrated in FIGURE 7 is what would take place if the arm 31 moved directly upward and was allowed to return directly downward without any extraneous forces being exerted on the arm. Due to the configuration of the cam 37 and the protrusion 40, however, this is not the case. When the cam 37 first engages the inclined side 42 of the protrusion 40, it exerts a force which has a horizontal as well as a vertical component. This horizontal component causes the arm 31 to move laterally a small amount concomitantly with the upward movement imparted to the arm by the vertical component. This same horizontal component is also present when the switch is being closed since the spring action of the arm 31 causes the protrusion 40 to move rapidly down the curved surface 38 of the cam 37. As a result of this horizontal force, the point of contact between the two contacts as the switch is being opened and closed does not follow the line AB as illustrated in FIGURE 8, but follows the dotted line from A' to B' and back to A''. A' being the point of contact when the switch is being closed and A'' being the point where the contacts break engagement when the switch is being opened. The reason why these two points are spaced apart is due to the fact that the horizontal component resulting when the switch is closing is not as great as the one which is exerted on the arm when the switch is being opened, since the cam is moving away from the protrusion 40 when the switch is being closed and the normal force existing between the protrusion 40 and the cam 37 is not as great at that time as it is when the switch is being opened by the cam 37.

This wiping action which takes place between the two contacts as the switch is opened and closed is very desirable in switches as is well known by those skilled in this art.

In operation, the unit operates in the conventional manner. By rotating the rotor or knob 11, the switch is either opened or closed and the contactor 22 is moved along the resistive element 21.

As stated above, the most common application of the commercial embodiment of this control is in hearing aid units mounted in the temple of the eyeglasses of the wearer. In this application the only knob needed to be exposed for adjustment by the operator is the rotor 11 which greatly simplifies the mounting of the hearing aid control in the eyeglass temple. In addition, the unique arrangement of parts which allows parts of the variable resistor to function also as switch components and vice-versa, results in a substantial reduction in the space required for the combination control. As an example of the space savings afforded by this invention, the commercial embodiment of this control is only .305" in diameter and .137" thick.

The invention claimed is:

1. A combination variable resistor and switch comprising:
  - a base of non-conductive material;
  - an arcuate resistive path supported by the base;
  - an electrically conductive shaft attached to and extending perpendicularly through the base;
  - a nonconductive member rotatably mounted on the shaft adjacent the resistive path;
  - a contactor carried by the member and arranged to

- move along the resistive path as the member is rotated on the shaft;
- a "U-shaped" resilient member having a first arm and a second arm embracing the control;
- the first arm being attached to the base and the second arm being resiliently urged toward the end of the shaft adjacent the rotating member; and
- cam means carried by the member for engaging the second arm and forcing the second arm away from and out of electrical contact with the shaft during a portion of the rotation of the member.
- 5
2. A switch comprising:
- a stationary contact having a generally spherical surface;
- a U-shaped member of resilient material having a first and second arm arranged with the first arm fixed with respect to the stationary contact, and with the second arm resiliently urged toward the stationary contact;
- a generally spherically shaped contact carried by the second arm; and
- means for moving the contacts into and out of engagement, said contacts being arranged with their vertical axes offset so that the contacts will make and break contact with a wiping action.
- 10
- 20
3. An electrical control comprising, in combination:
- a variable resistor having a stator section and a rotor section mounted on a common shaft, resistive and conductive paths, and contact means supported by the stator and rotor sections and arranged so that as the rotor section is rotated on the shaft relative to the stator section the contact means will move along the resistive path; and
- an electric switch having a stationary contact and a movable contact resiliently biased into engagement with the stationary contact; cam means carried by the rotor section of the variable resistor and arranged to hold the movable contact out of engagement with the stationary contact during a portion of the rotation of the rotor, the switch being further characterized by the fact that the stationary contact is the 40 end of the shaft of the variable resistor.
- 25
- 30
- 35
4. The electrical control of claim 3 in which the movable contact of the switch is carried by a U-shaped electrically conductive resilient member with one leg of the member being attached to the stator section and the other leg being arranged to resiliently hold the movable contact in engagement with the end of the shaft which supports the rotor.
- 45

5. The electrical control of claim 4 in which the movable contact and the stationary contact are spherically shaped and arranged with their vertical axes offset so that the contacts will make and break contact with a wiping action.
6. The electrical control of claim 4 in which the leg of the member which holds the movable contact in engagement with the stationary contact is provided with a V-shaped protrusion arranged to engage the cam means.
7. A combination variable resistor and switch comprising, in combination:
- a stator section for the variable resistor comprising a flat-sided base of insulating material, an arcuate resistance element supported by the base, and a shaft of conductive material fixed to the base and extending outwardly from both sides thereof;
- a rotor section for the variable resistor comprising a disc of insulating material rotatably mounted on the shaft adjacent the resistance element, and a contact carried by the disc arranged to move along the resistance element as the disc rotates on the shaft;
- a U-shaped member secured to one of the sections, a stationary contact formed on one end of the shaft, a movable contact disposed on an arm of the U-shaped member resiliently biased into engagement with the stationary contact; and
- cam means carried by the rotor section of the variable resistor arranged to engage a protrusion on the arm of the U-shaped member and hold the movable contact out of engagement with the stationary contact during a portion of the rotation of the rotor section; said switch being further characterized by the fact that the movable contact and the stationary contact are spherically shaped and arranged with their vertical axes offset so that the contacts will make and break contact with a wiping action.
